UNITED STATES PATENT OFFICE.

EDWIN J. STRONG, OF PLOVER, IOWA.

WAGON-BODY LIFTER.

SPECIFICATION forming part of Letters Patent No. 573,719, dated December 22, 1896.

Application filed October 22, 1896. Serial No. 609,668. (No model.)

To all whom it may concern:

Be it known that I, EDWIN J. STRONG, a citizen of the United States of America, residing at Plover, in the county of Pocahontas and State of Iowa, have invented certain new and useful Improvements in Wagon-Body Lifters; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to wagon-body lifters, and is designed more especially as an improvement upon my prior patent, dated July 21, 1896, No. 564,459.

The present invention consists in the general construction of the apparatus, including certain details, all as hereinafter fully set forth, and particularly pointed out in the claims.

In the accompanying drawings, forming part of this specification, Figure 1 is a side elevation of the apparatus with the parts in position to raise a wagon-body of the box type. Fig. 2 is a side elevation showing the position of the parts with the box or wagon-body elevated out of engagement with the running-gear of the vehicle. Fig. 3 is a plan view of Fig. 1. Fig. 4 is a detail view of the open frame which is used in connection with the wagon-box. Fig. 5 is a longitudinal sectional view showing the application of the apparatus for raising a hay-frame from the running-gear, the parts being in the position corresponding with Fig. 1. Fig. 6 is a plan view of Fig. 5.

The apparatus to be hereinafter described is located in a shed or other structure the ground or floor of which is preferably downwardly inclined rearward in order that the vehicle may be easily backed into position.

Referring to the drawings, the letters A designate the four corner-posts or uprights, which support the apparatus, said posts being located on each side of a driveway of sufficient width to accommodate an ordinary vehicle, and this driveway is preferably provided with parallel rails s s, that act to guide the vehicle into proper position between the

posts A. The posts on each side of the driveway are connected by a longitudinal beam B, which is mounted upon the upper ends of 55 said posts and rigidly secured thereto. Near the lower end of each post A are pivoted levers C, one on each side, and between the upper ends of these levers are pivoted longitudinal beams D, that normally rest upon the longitudinal beams B, the levers C being connected to the posts A and beams D in such manner that the latter may be elevated a suitable distance above the stationary beams B when said levers are swung to a vertical 65 position, stops b being secured to the forward ends of the stationary beams to limit such movement.

E E designate latches or notched bars, one being pivoted to the outer side of each movable beam D, and the notched ends e of these latches are adapted to engage pins b', which project from the stationary beams B, such engagement being accomplished when the beams D are elevated to their highest 75 point, and in order to prevent accidental disengagement of said latches the beams B are provided with holes so located that the removable locking-pins b², which engage therewith, will bear upon the lower ends of the 80 latches.

When the apparatus is intended for use in raising a wagon-box from its running-gear, Figs. 1, 2, and 3, stop-blocks d are mounted upon the movable beams D, and a cross-piece 85 T is placed upon the beams to bear against said stops and against a cross-piece t, secured to the under side of the wagon-box. In this connection the movable beams are also provided with their rear ends with uprights F, having bearings at their upper ends for a cross-bar G, carrying depending members g g, connected by a lower cross-bar g' to present an open frame which embraces the rear end of the wagon-box. The uprights F also support 95 a transverse shaft H, having spools h h, around which are wound flexible connections h', extending from the free ends of the latches or notched bars E, the shaft having a crank-handle for turning the same. This arrangement provides for simultaneously operating both latches. In raising the wagon-box from its running-gear the vehicle is first backed into the driveway between the posts A and

parts carried thereby, and when in position with the rear end of the box in engagement with the frame carried by the cross-bar G the cross-piece T is passed under the forward end 5 of said box to engage the stops d, carried by the movable beams D, and the cross-piece t, secured to the under side of the box. In this position a pawl U, which is pivoted to the under side of the wagon-box, is dropped to to engage the rear bolster of the running-gear, and then by wheeling the vehicle forward the pawl will act upon the wagon-box to push it forward, which movement being communicated to the beams D by the intervention of 15 the cross-piece T will swing the levers C to a vertical position, thus elevating the beams D and wagon-box carried thereby, in which position the parts are held by the latches or notched bars E engaging the pins b'. It will be understood that as the wagon-box is raised 20 the loops at the sides will disengage the standards of the running-gear, and when elevated the box will rest upon the cross-pieces T and g'. It will also be understood that as the 25 operation of raising the wagon-box depends principally upon the cross-piece T the whole wagon could be wheeled out by simply removing said cross-piece. In replacing the wagon-box the running-gear is backed into 30 position and the pawl U dropped to engage the rear bolster. Then by raising the latches E the weight of the box, in connection with that of the movable parts of the apparatus, will lower said box and simultaneously back 35 the running-gear, this operation being augmented by the inclination of the floor.

When the apparatus is arranged to raise a hay-frame from its running-gear, the stop-blocks d, uprights F, and parts carried by 40 said uprights are all removed, and after the vehicle has been backed into position with the cross-pieces of the frame located above the movable beams D swinging stops K at the forward ends of said beams are thrown to a vertical position to engage the forward 45 cross-piece of said hay-frame, and after the pivoted pawls V are dropped into engagement with the rear bolsters a forward movement of the vehicle will elevate the hay-frame 50 and beams D by said pawls pushing upon said hay-frame and the latter pushing upon the beams through the intervention of the stops K. These stops abut against pins k to prevent them swinging beyond a vertical position. 55

In connection with the wagon having the usual box-frame I prefer to use the pawl illustrated more clearly in Fig. 3, which consists of side members pivoted to blocks secured to 60 the under side of the box-frame and having a cross-bar that engages the bolster, and in connection with a hay-frame two pawls are preferably used, each consisting of a bar pivoted to one of the intermediate longitudinal beams 65 and having a notched end which engages the bolster.

The device herein shown and described pro-

vides a very simple, cheap, and effective apparatus, which can be readily adapted for raising either an ordinary box-frame or a hay-frame, and by providing the double levers C the movable beams B will be braced against lateral movement. 70

Having thus described my invention, what I claim as new, and desire to secure by Letters Patent, is—

1. In an apparatus for lifting and supporting wagon-bodies, the combination of the corner-posts located to provide a driveway between the same, longitudinal beams B secured upon the posts on each side of the driveway, levers C pivoted on the opposite sides of said corner-posts, and beams D pivoted between the upper ends of the levers above the stationary longitudinal beams; together with 80 latches or notched bars E pivoted to the movable beams, and pins b' attached to the stationary beams in position to engage the notched ends of the bars or latches when the movable beams are elevated, substantially as 85 shown and for the purpose set forth.

2. In an apparatus for lifting and supporting wagon-bodies, the combination, of the corner-posts located to provide a driveway between the same, longitudinal beams B secured upon the posts on each side of the driveway, levers C pivoted on the opposite sides of said corner-posts, and beams D pivoted between the upper ends of the levers above the stationary longitudinal beams; together with 95 latches or notched bars pivoted to the movable beams, pins attached to the stationary beams in position to be engaged by the latches or notched bars when the movable beam is elevated, a transverse shaft supported by the apparatus and provided with 100 spools carrying flexible connections which are connected to the pivoted latches, substantially as shown and for the purpose set forth.

3. In an apparatus for lifting and supporting wagon-bodies, the combination, of the corner-posts located to provide a driveway between them, longitudinal beams B secured upon the posts on each side of the driveway, levers C pivoted to the posts, and beams D 115 pivoted between the upper ends of said levers; latches or notched bars pivoted to the movable beams to engage pins carried by the stationary beams when said movable beams are elevated; together with uprights F on the 120 beams D, a cross-bar journaled in the upper ends of said uprights, an open frame carried by said cross-bar, stops mounted on the movable beams, a cross-piece adapted to engage 125 said stops and a fixed part of the wagon-body, and a pawl carried by the wagon-body to engage a bolster of the vehicle, substantially as shown and for the purpose set forth.

4. In an apparatus for lifting and supporting wagon-bodies, the combination, of the corner-posts located to provide a driveway between the same, longitudinal beams B secured upon the posts on each side of the driveway, levers C pivoted to the corner-

posts, longitudinal beams D pivoted to the upper ends of the levers, means carried by the movable beams which are engaged by the wagon-body to limit the forward movement of said wagon-body upon said beams, latches or notched bars pivoted to the movable beams, and stationary pins with which said latches engage when the beams are elevated; together with a pawl pivoted to the under side of the wagon-body to engage one of the bolsters of the vehicle, substantially as shown and for the purpose set forth.

5. In an apparatus for lifting wagon-bodies, the combination, of the corner-posts located to provide a driveway between the same, levers C pivoted to the posts on opposite sides

thereof, beams D pivoted between the upper ends of the levers; together with pivoted latches carried by the movable beams, and stationary pins with which said latches engage when the movable beams are elevated; the parts being adapted to be used in connection with a vehicle having a pawl pivoted to the wagon-body to engage one of the bolsters of the vehicle, substantially as shown and for the purpose set forth.

In testimony whereof I affix my signature in presence of two witnesses.

EDWIN J. STRONG.
